UNITED STATES PATENT OFFICE.

RICHARD HENRY WILDER, OF PORT HURON, MICHIGAN, ASSIGNOR OF ONE-HALF
TO WILLIAM C. BOWEN, OF PORT HURON, MICHIGAN.

PRINTING PRESS.

Application filed January 19, 1922. Serial No. 530,236.

To all whom it may concern:

Be it known that I, RICHARD HENRY WILDER, a citizen of the United States, residing at Port Huron, county of St. Clair, 5 State of Michigan, have invented a certain new and useful Improvement in Printing Presses, and declare the following to be a full, clear, and exact description of the same, such as will enable others skilled in 10 the art to which it pertains to make and use the same, reference being had to the accompanying drawings, which form a part of this specification.

My invention relates to improvements in 15 printing presses. It particularly relates to inking mechanism adapted for use in connection with the flat bed type of printing press.

An object is to provide in connection 20 with the flat bed printing press of a plateless type, rotary distributing rollers adapted to pick up and convey the ink from the fountain to the form rollers.

Another object is to provide in connection 25 with the mechanism used to pick up the ink from the fountain and convey it to the form rollers, means adapted to distribute the ink in well defined longitudinally segregated blocks on said form rollers.

These and other objects, together with 30 details of construction and operation, will more fully appear from the following specification, appended claims and accompanying drawings, in which:

Figure 1 is a side elevation of a printing press equipped with my device.

Fig. 2 is a fragmentary plan of the distributing rollers.

Fig. 3 is a cross section taken on line 40 3-3 Fig. 2.

Fig. 4 is an elevation of a divided steel roller.

Fig. 5 is a cross section taken on line 45 5-5 Fig. 4.

Fig. 6 is a plan of the printing press including the form rollers.

Fig. 7 is an elevation of a divided steel roller showing the individual sections separated from each other.

Fig. 8 is a similar side elevation showing the separate sections juxtaposed.

Fig. 9 is an elevation of the lower connection of oscillating arm 39.

Fig. 9^a is an elevation of the construc-

tion shown in Fig. 9, but taken at right 55 angles to the view in Fig. 9.

In the drawing let 10 indicate the frame of a printing press. A power driven gear is indicated as 11, which gear 11 engages another gear 12. Mounted on the same 60 shaft with gear 12 is gear 13 which in turn engages large gear 14, which gear 14 is mounted on shaft 15. Likewise mounted on shaft 15 is gear 16 which gear 16 engages another gear 17. Positioned above 65 large gear 14 and engaged therewith is small gear 18. Mounted upon the same shaft as gear 18, so as to rotate therewith, is a pulley 19 which drives a chain 20 which chain engages a pulley 21 carried by the 70 roller 22 so as to provide a drive for such roller. A second drive chain 23 extends to steel roller 24 to drive this roller.

Rollers 30, 24 and 25 are linked together as shown in Figs. 2 and 3, so that they vibrate longitudinally as they are rotated. 75 This is an old practice in printing press construction. The longitudinal vibration is of small extent and is intended to cut the ink on the rollers. It is provided for, as 80 shown in Fig. 3, by means of a gear 26 splined to the roller shaft 25^a which carries the roller 25 which gear 26 engages a gear 27 which gear 27 is carried by a shaft 27^b provided with a head 27^c, which shaft 85 is mounted in bearing 28^a carried by the press. This gear is provided with a worm 28 which worm engages a carriage member 29, carried by a bar 29^a as shown in Fig. 3. This bar connects individual carriage members 29 which are mounted upon extensions of the roller shafts upon which rollers 30, 24 and 25 are mounted so that as the threaded shaft, or worm, 28 is reciprocally rotated the bar vibrates back and forth laterally and produces a longitudinal vibration 90 of the several roller shafts and rollers concurrently with the vibration of roller 25. The roller 25 is driven by means of the reciprocating rack member 27^a which 95 meshes with gear 27 to reciprocally rotate the same. This is standard construction.

The rollers 30 and 24, comprise a roller core or central shaft upon which is mounted movable longitudinal sections as shown in 100 Figs. 5, 7 and 8. Roller 24 may be taken as typical construction. The core is preferably rectangular in cross section and in-

dicated by the subletter "a" as 24^a. Removable, separable, longitudinal roller sections are provided which may be inserted on this core and secured at adjusted positions by 5 any conventional means such as set screws 31. This feature forms part of my invention.

In color work it is particularly desirable that the line of demarkation between the 10 separate colors be preserved. For example if four divisions of color were desired, the steel rollers might be divided as shown in Fig. 6, in which four distinct longitudinal sections are separated from each other so 15 that each section may carry its own particular color and this color preserved throughout the succeeding series of corresponding sections. This would provide a sharp dividing line between the separate 20 colors intended for use, and prevent the colors overlapping each other, running together and thereby lowering the quality of the work.

In the conventional type of construction, 25 where a continuous roller is used, there is a tendency at all times for the ink to run together on the roller and the line of contact between the sections of differently colored ink on the roller becomes blurred and produces an unsightly appearance. This tendency is accentuated because of the longitudinal vibration of the rollers. It is further accentuated by the reciprocating action 30 of the plate, which forms a part of the conventional printing press and which plate takes the ink from the rollers and conveys it to the form rollers 32 and 33. In my invention I maintain the color division by providing separate longitudinal roll sections. 35 It is obvious that the color divisions in the fountain would agree with the divisions on the roller sections and that the whole would be uniform.

I omit the reciprocating plate found in 40 the conventional press and provide instead as the particular feature of my improvement a rotary form of distribution for conveying the ink from the fountain roller 34 to the form rollers 32 and 33. The fountain 45 itself is indicated as 35 and provided with relatively movable dividers 35^a which are adapted to divide the fountain into separate ink containing compartments.

My rotary distribution system comprises 50 a series of movable rollers mounted for lateral movement as a unit alternating with the divided steel rollers and adapted for movement so as to receive ink from the steel 55 roller nearest the fountain and conveying it to the succeeding roller further away. These 60 movable rollers are indicated as 36, 37 and 38 and are carried by arms of an oscillating frame or bracket 39 pivoted to the press frame as at 40. The lower end of this 65 bracket is pivoted at 41 to a cam actuated

link 42. This cam action of the link is shown in Figs. 9 and 9^a. The link is enlarged over the shaft 15 on which is mounted large gear 14. The link carries opposed cam engaging rollers 43 and 44 which are 70 engaged by a cam 45 mounted on shaft 15. This cam is so shaped as to rock the arm or bracket 39 about its pivot 40 in such a manner that the rollers 36, 37 and 38 are moved laterally as a unit forward and backward. 75 Roller 36 takes the ink from fountain roller 34 and conveys it to the divided steel roller 24. Roller 37 takes the ink from divided steel roller 24 and conveys it to roller 22. Roller 38 takes the ink from roller 22 and 80 conveys it to divided steel roller 30. Roller 30 deposits the ink on the form roller 32. This completes the function of the machine so far as my invention is concerned. The ink is of course deposited by the form rollers 85 on the form itself.

The movable rollers provided for the rotary distribution take the colors in blocks from the divided steel rollers and deposit the same on the form rollers in like divided 90 blocks. In the old construction where a plate was used the ink would run together on the plate. There would always be a certain amount of overlapping. In rough work this would not be important. In quality 95 work, however, it becomes exceedingly important. My construction also permits of a shortening of the press frame itself in that the rotary type of distribution takes up less space than the distribution provided for by 100 the use of a reciprocating plate.

What I claim is:

1. In the inking mechanism for a flat bed printing press, in combination with the ink fountain and fountain roller, form rollers, a series of rotatably mounted stationary and movable rollers adapted to pick up and convey the ink from the fountain rollers to the form rollers, and a rock frame carrying and simultaneously moving the movable rollers. 105

2. In a printing press, that combination in the inking mechanism which comprises the fountain and fountain roller and the form rollers of a series of stationary spaced apart rolls positioned intermediate the fountain roller and form rollers, an alternating series of movable rollers, and a cam-operated rock frame for reciprocating said movable rolls so that through the medium of said movable rollers and said stationary rollers, ink will be conveyed from the fountain roller to the form rollers. 115

3. In inking mechanism for a printing press, in combination with the fountain roller and form rollers, a series of stationary spaced apart rollers positioned between said fountain roller and form rollers, an alternating series of reciprocally movable rollers adapted to pick up the ink from the fountain roll and distribute it on the stationary rollers 125 130

and pick up the ink from the stationary rollers and distribute it on the form rollers, and a rock frame having a plurality of sets of arms, each set carrying one of the movable rollers.

4. In a printing press, in combination, a fountain roller, form rollers, a plurality of rotatably mounted spaced apart steel rollers disposed intermediate said fountain roller and form rollers, each of said steel rollers comprising a shaft member carrying a series of removable longitudinal sections adapted

to be continuously or separably positioned on said shaft, a series of movable rollers positioned in alternating relationship with 15 said stationary rollers and so mounted as to be moved as a unit first in one direction then the other to pick up the ink from the fountain rollers and distribute it on the form rollers through the medium of the 20 steel rollers.

In testimony whereof I sign this specification.

RICHARD HENRY WILDER.
